UNITED STATES PATENT OFFICE.

HAROLD W. HOLLENBECK, OF KIRKLAND, WASHINGTON, ASSIGNOR TO DURABLE MAT COMPANY, OF SEATTLE, WASHINGTON, A CORPORATION OF WASHINGTON.

DESIGN FOR A FLOOR MAT.

Application filed January 10, 1929. Serial No. 29,566. Term of patent 3½ years.

To all whom it may concern:

Be it known that I, HAROLD W. HOLLENBECK, a citizen of the United States, residing at Kirkland, in the county of King and State of Washington, have invented a new, original, and ornamental Design for a Floor Mat, of which the following is a specification, reference being had to the accompanying drawing, forming part thereof.

I claim:

The ornamental design for a floor mat, as shown.

HAROLD W. HOLLENBECK.
